J. E. LIMBACHER,
OIL BURNER,
APPLICATION FILED APR. 25, 1916.

1,197,217.

Patented Sept. 5, 1916.

UNITED STATES PATENT OFFICE

JOHN E. LIMBACHER, OF ST. MARYS, OHIO.

OIL-BURNER.

1,197,217.

Specification of Letters Patent. Patented Sept. 5, 1916.

Application filed April 25, 1916. Serial No. 93,405.

To all whom it may concern:

Be it known that I, JOHN E. LIMBACHER, a citizen of the United States, residing at St. Marys, in the county of Auglaize and State of Ohio, have invented certain new and useful Improvements in Oil-Burners; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to new and useful improvements in oil burners of a type adapted to control the passage of the oil to a point where it is deflected in a thin film to currents of air and whereby a thorough mixture of the oil with air is effected.

20 The object of the invention is to provide an oil burner wherein a proper mixture of the air and oil is accomplished, and the consumption of oil is minimized while the resulting heat due to the combustion of the fuel thus obtained is of a maximum degree.

25 In carrying out my invention, I provide a valve member constructed and arranged to control the flow of oil to the mixing point, 30 and to deflect or spread the oil into a film at such points where it meets currents of air and becomes thoroughly impregnated therewith.

35 The accompanying drawing illustrates my improved oil burner in an operative position in a furnace and reference is made to said drawing wherein—

40 A represents the fire-brick wall of the furnace within which is mounted a pipe B. This pipe is shown as broken away in the drawing but it will be understood that the said pipe receives air under suitable pressure and conducts it to a point in the furnace where it mixes with the oil. Inclosed 45 within the pipe B is a burner pipe C connecting with the oil feed pipe D by means of a screw-threaded sleeve E. The burner pipe C is supported in a position in the pipe B by means of a bracket F which lies near the end of the burner pipe C and rests upon the bottom of the air pipe B. The position 50 of the burner pipe C is such that its discharge end lies backward from the exhaust end of the pipe B a distance substantially 55 as shown in the drawing so that the oil and air are mixed at the entrance to the furnace

combustion chamber G. The pipe D passes out of the air pipe B and is coupled to a section of pipe H which is exteriorly screw-threaded at each end. The pipe D is also screw-threaded at both ends and the end thereof which extends out of the pipe B is coupled to the section H by a T-fitting I which also receives an end of an oil supply pipe J which extends from the source of supply. This oil supply pipe J is provided with a valve K which controls the passage of oil to the pipe D. The section of pipe H is provided with a packing gland L. A valve rod formed of sections M and N projects through the several pipes H, D and C, the two sections being connected at O. The section M of said rod is screw-threaded a portion of its length as at P and said screw-threaded portion engages the interior screw-threads of the pipe section H and passes through the packing gland L and receives a hand wheel Q by means of which the said rod is manipulated. On the inner end of said sectional rod a conical-shaped head R is secured. This conical-shaped head performs the function of a valve in connection with the end of the burner pipe C and it also acts as a deflector to spread the oil in a film-like sheet as it discharges from the burner pipe C. The oil is thus discharged in the air pipe B where it meets the currents of air and mixes thoroughly therewith just as the resulting mixture is admitted to the combustion chamber G.

Having described my invention, I claim.

An oil burner, comprising an air pipe mounted in a furnace wall and having its discharge end in a position to discharge to the combustion chamber of said furnace, a burner pipe mounted in said air pipe and having its discharge end lying inwardly in the discharge end of the air pipe, an oil feed pipe of smaller diameter than the burner pipe connected thereto said oil feed pipe being connected with a pipe of smaller internal diameter, an oil supply pipe connected with said oil feed pipe at a point between the ends of the oil feed pipe and the pipe of smaller internal diameter, a conical-shaped head coöoperating with the discharge end of the burner pipe to control the passage of oil therethrough and to deflect the oil discharging therefrom in a film-like body into the discharge end of the air pipe, a sectional rod connected to said conical-shaped head and extending through the burner pipe, the oil

feed pipe and the pipe of smaller internal diameter, the section of said rod extending through the pipe of smaller internal diameter having a screw-threaded connection therewith, and a hand wheel mounted on the end of said last named rod section whereby said sectional rod may be turned to vary the position of the conical-shaped head with

relation to the discharge end of the burner pipe, substantially as specified.

In testimony whereof I affix my signature, in presence of two witnesses.

JOHN E. LIMBACHER.

Witnesses:

A. J. INDERRIEDEN,
LOUIS K. SCHMIDT.
